Primary Examiner — Vy N Koenig*Assistant Examiner* — Qiawen W Wiechert(74) *Attorney, Agent, or Firm* — Hawaii Patent Services;
Nathaniel K. Fedde; Kenton N. Fedde(57) **CLAIM**

The ornamental design for a foldable cushion, as shown and described.

DESCRIPTION

FIG. 1 is a front, left, top perspective view of a foldable cushion, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 3;

FIG. 10 is a front, left, top perspective view of its reduced scale in an alternate configuration; and,

FIG. 11 is a front, left, top perspective view of its reduced scale in an alternate configuration.

The dash-dot-dash broken lines are for notating the boundaries of the enlarged view and form no part of the claimed design.

1 Claim, 11 Drawing Sheets(56)
